(57) **CLAIM**

The ornamental design for a utensil handle, as shown and described.

DESCRIPTION

FIG. 1 is a side, top perspective view of the utensil handle showing our new design, the broken lines showing the attached neck and spoon portion and clip attached to the rear of the handle are for illustrative purposes only and form no part of the claimed design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is a top plan view of an alternate embodiment of FIG. 1 the only difference being no holes for the clip at the rear of the handle as illustrated in FIG. 1.
